INGOT SCALPING MACHINE

William J. Trettheway, Henderson, Nev., assignor,
by mesne assignments, to the United States of
America as represented by the Secretary of the
Navy

Application February 16, 1945, Serial No. 578,203

3 Claims. (Cl. 90—21)

1

This invention relates to an ingot scalping machine and has for its object the provision of an improved machine of this character. More particularly, the invention is concerned with a machine for scalping non-ferrous ingots such as those cast of magnesium and the like, and provides means for feeding the ingots to a scalping cutter as well as resilient means for holding the ingot in a firm position while it is being cut by the cutter.

The invention, in its more complete and advantageous embodiments, comprises an ingot feed mechanism, preferably comprising an endless chain with means thereon for engaging each ingot and feeding it to the cutter, means for guiding the ingots and preventing lateral movement thereof, and resilient means arranged to bear on the ingots and hold them in position while they are being fed to the cutter. While any suitable scalping cutter may be used, a milling head, especially one rotating on a vertical shaft above the ingots, is very effective for the purposes of the invention. The machine is especially effective for scalping long, narrow and notched ingots, especially those tapering in cross-section towards the bottom, and includes a guideway in which the chain travels to feed the ingots under the milling head thereabove which cuts away the upper surface of the ingot. The chain preferably is fitted with a number of dogs, each of which engages a notch in the ingot and pushes it under the milling head. A plurality of rubber covered rollers operating under spring tension are mounted on the machine above the chain and arranged to bear on the ingots and press them into a secure position while they pass under the milling head. The chain feed is preferably driven by its own motor through a speed reduction gear and the milling head is preferably driven directly by its own motor.

These and other novel features of the invention will be better understood after considering the following discussion taken in conjunction with the following drawings, in which:

Fig. 1 is a plan view of apparatus embodying the invention;

Fig. 2 is a side elevation of the apparatus of Fig. 1;

Fig. 3 is an end elevation of the apparatus of Fig. 1;

2

Fig. 4 is a view along line 4—4 of Fig. 1;

Fig. 5 is a side view of an ingot of the type especially suited for scalping by the apparatus of the invention; and

Fig. 6 is a sectional view somewhat similar to that of Fig. 4 showing a modification.

The apparatus illustrated in the drawings comprises a steel supporting structure having a low table portion 1, a high table portion 2 attached thereto, and an upright frame 3 attached to the table 2. The chain base plate 4 has two parallel grooves milled therein providing a track 5 for guiding the endless roller chain 6 which passes over the sprockets 7 and 8. The guide plates 10 and 11 are adjustably attached to the plate 4 and are spaced apart sufficiently to provide a channel or groove through which the ingots 12 are fed in engagement with the inclined faces 13 and 14 respectively.

As best shown in Figs. 4 and 5, the ingots are long and narrow of wedge-shaped cross-section with a mold notch 15 in the under surface, the top surface 16 being opposite and of relatively greater width than the bottom surface 17. The chain 6 has a plurality of spaced dogs 18 attached thereto which engage the notch 15 of the ingot to positively feed it in the direction of chain travel.

The motor 20 on the table 1 is connected by shaft 21 to the speed reduction gear 22 which is connected by shaft 23 to the sprocket 8 for driving the chain 6 in the direction of the arrow. A plurality of pressure rollers 24 are mounted on the base plate 4 and above the ingots 12 being fed along the chain. As best shown in Fig. 4, the rollers 24 have an exterior layer of resilient rubber 25 and are mounted upon shafts 26 arranged transverse to the chain 6. The end of each shaft is attached to a bearing bracket 27 to which is attached a rod 28 slidably mounted in a suitable hole through the plate 4, table 2 and guides 10 and 11. Each rod has a spring 30 and adjusting nut 31 for urging the roller 24 downwardly and into pressing engagement with the top surface of the ingot 12 thereunder. The motor 35 mounted on the frame 3 has a vertical shaft 36 to which is attached the rotary milling head 37 which carries a plurality of cutters 38 adjustably mounted in the disc 39.

As best shown in Figs. 1 and 2, there are four

of the rollers 24 on the right or entrance end of the guides 10 and 11 through which the ingots are fed by the chain 6 under the milling head 37 and there are two such rollers 24 on the opposite or discharge side. The milling head is so adjustably positioned with respect to the upper surface of the ingot that the cutters 38 cut off the desired layer from the upper surface of the ingot as it is fed thereunder. The upper surface of ingots is usually irregular and the resilient rubber layer 25 adjusts the rollers to these irregularities making it possible for the springs 30 to exert the desired downward pressure on the ingot to hold it in a firm position while it is being cut by the milling head.

It will be apparent from the arrangement of apparatus illustrated that there are distinct advantages in the use of two motors, one for driving the chain at a positive reduced speed and another motor for driving the milling head at a relatively great speed.

The modified apparatus illustrated in Fig. 6 comprises two chains 40 and 41 travelling in track grooves 42 and 43, respectively, in the base plate 44. There are three guides 45, 46 and 47 for guiding the two ingots 48 and 49. The shaft 50 has mounted thereon the rollers 51 and 52 similar to the rollers 24 of Fig. 4.

In using the apparatus of the invention for scalping magnesium ingots, for example, the ingots are placed on the chain at the right end of table 2, as shown in Fig. 2, and as one of the dogs 18 engages one of the notches 15, the ingot is fed through the milling head. A chain speed of approximately 90 inches per minute allows practical operation by one man. The springs 30 may be adjusted to allow for irregularities in ingot sizes and to keep a constant pressure on the upper surface of the ingots. As shown in the drawings, the milling head rotates clockwise which is opposite to the direction of travel of the ingot.

The apparatus of the invention may be used for scalping any non-ferrous ingots or similarly shaped bodies formed of plastic material.

I claim:

1. Apparatus for scalping long narrow notched ingots of tapered cross-section which comprises a trough-like horizontally disposed guide in which the ingots are fed, the guide being shaped to hold the flat tapered sides of the ingots in a close fit, a milling head mounted above the guide arranged to cut off the upper surface of the ingots, an endless chain having dogs spaced thereon for engaging the notches in the ingots, means for driving the chain through the guide to feed the ingots to the milling head, and resilient means ad-

jacent the milling head and above the guide cooperating with the guide to hold the ingots in a firm position to prevent rotation during the scalping operation.

5 2. Apparatus for scalping long narrow notched ingots of tapered cross-section which comprises a trough-like horizontally disposed guide in which the ingots are fed, the guide being shaped to hold the flat tapered sides of the ingots in a close fit, a milling head mounted above the guide arranged to cut off the upper surface of the ingots, an endless chain having dogs spaced thereon for engaging the notches in the ingots and passing through the trough-like portion of the guide,

10 means for driving the chain through the guide to feed the ingots to the milling head, and resilient means adjacent the milling head and above the guide cooperating with the guide to hold the ingots in a firm position to prevent rotation during the scalping operation.

15 3. Apparatus for scalping long narrow notched ingots of tapered cross-section which comprises a trough-like horizontally disposed guide in which the ingots are fed, the guide being shaped to hold the flat tapered sides of the ingots in a close fit,

20 a milling head mounted above the guide arranged to cut off the upper surface of the ingots, an endless chain having dogs spaced thereon for engaging the notches in the ingots and passing through the trough-like portion of the guide, means for driving the chain through the guide to feed the ingots to the milling head, and a plurality of rubber covered rollers each provided with spring means forcing the rollers into pressing engagement with the upper surface of the ingot being cut, said rollers cooperating with the guide to hold the ingots in a firm position to prevent rotation during the scalping operation.

WILLIAM J. TRETHEWAY.
